DISPLAY TRAY FOR PACKAGED GOODS

Jerome Bell, Schoolcraft, Mich., assignor to The Upjohn Company, Kalamazoo, Mich., a corporation of Delaware

Filed June 8, 1959, Ser. No. 56,275

Term of patent 14 years

(Cl. D80—9)

fig. 1

I claim:

The ornamental design for a display tray for packaged goods, as shown.
